UNITED STATES PATENT OFFICE.

HARVEY P. MCFARLAND, OF BURLINGTON, IOWA, ASSIGNOR OF ONE-HALF TO
CHARLES W. BALDRIDGE, OF CHICAGO, ILLINOIS.

RAIL ANCHOR.

1,405,604.

Specification of Letters Patent. Patented Feb. 7, 1922.

Application filed August 31, 1921. Serial No. 497,175.

To all whom it may concern:

Be it known that I, HARVEY P. MCFARLAND, a citizen of the United States, residing at Burlington, in the county of Des Moines and State of Iowa, have invented 5 certain new and useful Improvements in Rail Anchors; and I do hereby declare the following to be a full, clear, and exact description of the invention, such as will 10 enable others skilled in the art to which it appertains to make and use the same.

This invention relates to a rail anchor of the type designed to prevent forward movement or creeping of the rail and comprising a device arranged to be attached to the rail and to bear against one of the cross ties to which the rail is secured.

It is an object of this invention to provide such a device of few and simple parts 20 which can be quickly attached to and removed from the rail.

It is a further object of this invention to proconstruct such a device having a member underlying the rail, an anchor block 25 mounted thereon and co-operating therewith to clamp the rail, together with a detachable clamping means adapted to bear against the anchor block and move the same into and hold the same in clamped position.

These and other objects and advantages of the invention will be fully set forth in the following description made in connection with the accompanying drawings in 35 which like reference characters refer to the same parts throughout the different views and in which—

Fig. 1 is a side elevation of the device, a portion thereof being shown in section and 40 showing the same applied to a rail;

Fig. 2 is a top plan view of the device shown in Fig. 1; and

Fig. 3 is a sectional view taken on the line 3—3 of Fig. 1, looking in the direction 45 of the arrows.

Referring to the drawings, a standard type of rail is shown as *a*, which is secured in the usual manner to a cross tie connected at *b*. The rail anchor proper comprises a 50 member 1 known as a hook bar which is of general rectangular cross section and provided at one end with an upwardly extending hook portion 1^a. The bar 1 is adapted to underlie the rail and extend transversely 55 of the same and the hook 1^a is adapted to

contact with the side and overlie one edge of the rail flange. The bar 1 has adjacent its other end a slot 1^b extending therein from its top surface and projecting downwardly toward said end. Mounted to slide 60 upon the bar 1 and having an opening through which said bar extends is an anchor block 2 formed at its top portion as a hook member adapted to contact the edge of and extend over the rail flange opposite the side 65 contacted by the portion 1^a of the hook bar. The member 2 extends down the sides of and under the bar 1 and one side thereof is lengthened by an extension 2^a, as shown in Figs. 1 and 2, and this side of the anchor 70 block 2 is adapted to contact the side surface of the cross tie *b*. The device also comprises a pawl member 3 formed with a bifurcated eccentric hub having a pin 4 extending through the center thereof and between said bifurcations. The pawl is arranged to be disposed with the bifurcations thereof straddling the bar 1 with the pivot 75 pin 4 seated in the bottom of the slot 1^b. When the pawl is rotated about its pivot 80 the eccentric hub portion thereof will bear against the outer side of the anchor block 2 and move the same toward the hook end of the bar 1, thus clamping the rail firmly 85 between said hook portion and anchor block. The pawl 3 is provided with a handle portion 3^a by which it is swung and this portion is also arranged to act as a stop and contact with its concave surface, the top 90 of the anchor block 2, in which position the longest radius of the eccentric hub is in contact with the anchor block. The anchor block 2 is provided with cutaway portions 2^b at each side to lessen the weight 95 thereof.

The operation of the device will be apparent from the above description but the same may be briefly summarized as follows:

The bar 1 is placed under the rail with the hook portion 1^a extending over one side 100 of the flange thereof. The anchor block 2 is then moved against the other side of the rail extending over the flange thereof. The pawl 3 is then placed in the slot 1^b in the position shown in dotted lines in Fig. 1 and 105 then swung to the position shown in full lines, which motion will move the anchor block 2 into firm clamping relation with the rail and hold the same in position. The parts are thus assembled with the edge of 110

the anchor block in contact with the side surface of the tie *b*. The rail is thus firmly and rigidly clamped and any creeping thereof longitudinally, relatively to the cross tie, is prevented.

From the above description it is seen that applicant has provided a rail anchor of three simple and quickly removable parts which anchor can be quickly applied to the rail and as quickly removed therefrom. The parts can be made rigid and with little expense. When once made, they have no tendency to become disarranged or broken.

It will, of course, be understood that various changes may be made in the form, details and proportions of the parts without departing from the scope of applicant's invention, which generally stated, consists of the matter shown and described and set forth in the appended claims.

What is claimed is:

1. A rail anchor comprising a member underlying a rail and arranged to extend over the flange at one side thereof, means movable relatively thereto for clamping the rail adapted to contact with the cross tie, and cam means detachably engaging said member for clamping said means against the rail.

2. The structure set forth in claim 1, the first mentioned means comprising a member embracing and movable on said first mentioned member.

3. A rail anchor having in combination a hook member having a hook at one end adapted to receive one edge of the rail flange, an anchor block slideable thereon and adapted to extend over the opposite edge of the rail flange and to contact with its side surface the side of a cross tie, an eccentric means carried by said bar engaging with said block to move and hold the same in clamping relation to the rail.

4. A rail anchor having in combination a

substantially rectangular bar adapted to extend transversely under the rail, an anchor block mounted for sliding movement on said bar arranged to extend under and over the opposite edge of the rail flange and to co-operate with said bar in clamping the same and an eccentric adapted to bear against said block and move the same in clamping relation to said rail.

5. The structure set forth in claim 4, said pawl having a handle extension thereon and adapted to contact with the top of said block to limit the movement of said pawl.

6. A rail anchor comprising three members, a bar having a hook at one end and a slot formed therein at the other, an anchor block slideable on said bar and co-operating with said hook to clamp the rail, and a removable clamping member adapted to be received in said slot in said bar.

7. The structure set forth in claim 6, said clamping member comprising a bifurcated eccentric hub having a transverse pivot pin secured therein and extending between said bifurcations, said pin adapted to seat in said slot in the bar so that when rotated about said pin the eccentric hub will move said anchor block to hold the same in clamping position.

8. A rail anchor having in combination a hook bar transversely underlying the rail with the hook extending over one edge of the flange thereof, an anchor block slideable thereon having a hook extending over the opposite flange edge of the rail and a removable eccentric clamping pawl seated and rotated in a slot formed in the other end of the bar.

In testimony whereof I affix my signature in presence of two witnesses.

HARVEY P. McFARLAND.
